UNITED STATES PATENT OFFICE.

WALTER J. BLIFFERT, OF MILWAUKEE, WISCONSIN.

COMBINED VAPORIZER AND AUXILIARY AIR-INLET DEVICE.

Application filed November 22, 1923. Serial No. 676,369.

To all whom it may concern:

Be it known that I, WALTER J. BLIFFERT, a citizen of the United States, and resident of Milwaukee, in the county of Milwaukee 5 and State of Wisconsin, have invented certain new and useful Improvements in Combined Vaporizer and Auxiliary Air-Inlet Devices; and I do hereby declare that the following is a full, clear, and exact description thereof.

This invention relates to manifold gaskets and is particularly directed to a manifold gasket adapted to be inserted between the intake manifold and the carburetor of 15 an internal combustion engine.

Objects of this invention are to provide an intake manifold gasket which will interrupt the flow of the film of condensed fuel along the sides of the intake manifold, which will 20 heat such fuel and mix it with incoming fresh air, thus securing thorough vaporization, which will then direct the vaporized fuel centrally of the intake manifold to prevent subsequent condensation, and to provide 25 a manifold gasket which will secure such heating and vaporization of the flowing film of liquid fuel without injecting any burnt gases into the mixture.

Further objects are to provide a manifold gasket which is constructed in a very simple and practical manner, which may be 30 quickly applied to a standard type of car, and which is highly serviceable in operation.

35 An embodiment of the invention is shown in the accompanying drawings, in which:—

Figure 1 is a view illustrating the gasket in position with reference to the intake and exhaust manifolds and carburetor.

40 Figure 2 is an enlarged sectional view on the line 2—2 of Figure 1.

Figure 3 is a face view of the gasket partly in section.

45 Figure 4 is a view of the conventional type of manifold and butterfly valve illustrating the distribution of fuel with reference to such parts.

The gasket comprises a flat body portion 1 provided with outwardly projecting ears 50 conforming to the ears 2 and 3 of the carburetor and intake manifold 4 and 5, respectively. These ears are apertured, as indicated at 6, to receive the clamping bolts, as shown in Figure 2. This gasket is provided with a central aperture 7 which is of 55 less extent than the corresponding apertures

of the intake manifold and the adjacent portion of the carburetor, as shown in Figure 2. The interior surface of the aperture is beveled, as clearly shown in Figure 2, and it will be noted that the aperture is not exactly centrally located with reference to the intake manifold but the marginal walls project, as indicated at 8, a greater distance on one side of the bore of the intake manifold than the portion 9 on the other side thereof. It is to 60 be noted that the lesser projection 9 is located adjacent the trailing portion 10 of the butterfly valve and that the greater projecting portion 8 is located on the same side as the leading portion 11 of such butterfly 65 valve for a purpose hereinafter to appear.

This gasket is provided with an upper and a lower opening through which projects a pipe 12 which is provided with a uniform bore or opening 13 throughout the major 70 portion of its length and with a constricted upper outlet 14, as shown in Figure 3. The lower end of the pipe 12 projects beyond the bottom of the gasket and is attached to a flexible tube 15. The upper end of this tube 75 opens into the exhaust manifold 16, as shown in Figure 1, and thus supplies heated gas to the pipe 12.

It is to be noted from reference to Figure 2 that the pipe 12 is provided with a flat 80 forward face 17 and that its rear face is curved.

It is thought that the operation of the apparatus will be more clearly understood from a reference to Figure 4 which illustrates the 85 action of the conventional type of butterfly valve and intake manifold 5'. This butterfly valve, it will be noted, is shown as occupying the same position as that in Figure 2 with its trailing edge 10' and its lead edge 90 11' in close proximity to the walls of the delivery portion 18 of the carburetor. It has been found, and it is apparent from an inspection of Figure 4 that the greater quantity 95 of the mixture flows past the trailing portion 10' of the valve and that a lesser portion thereof passes by the leading portion 11'. Experiments indicate that approximately three quarters of the mixture passes 100 the trailing portion of the valve and about one quarter passes the leading portion thereof. For this reason, therefore, a lesser obstruction is provided by the projecting part 9 of the gasket adjacent the side having the greater flow of the mixture than is offered 105 by the greater projection 8 which encounters 110

the lesser volume of flowing mixture. In addition to this, the gasket is provided with a fresh air inlet or duct 19 (see Figures 2 and 3) which opens through the portion 9 5 and provides additional air for vaporizing the liquid portions of the mixture. It will be seen from Figure 2 that the mixture together with the film of liquid fuel is violently projected inwardly into contact with 10 the heated pipe 12 and is also mixed with the incoming fresh air through the duct 19. This vaporized fuel is thus heated and intimately mixed with a stream of fresh air and occupies substantially the central portion of 15 the intake manifold 5, as illustrated in Figure 2, thus avoiding further contact with the walls of the manifold and preventing further condensation.

It is to be noted from reference to Figures 20 2 and 3 of the drawing that the inlet duct 19 for the fresh air opens into the aperture through the gasket at a point spaced rearwardly of the forward shoulder or constricted portion of the gasket. This insures an inward flow of air through the duct as the pressure rearwardly of the shoulder is less than the pressure forwardly thereof due to the particular conical shape of the bore of 25 the gasket.

30 This guiding of the thoroughly vaporized moisture away from the walls of the manifold, obviously will persist for a considerable distance into the intake manifold 5. It is to be noted, however, that as the upper 35 portion of the manifold is approached and distribution to the various cylinders begins that the mixture then is within a heated portion of the intake manifold.

40 It is further to be noted that the heated gases discharged through the outlet 14 of the heated pipe 12 are swept backwardly across the carburetor and thus keep the carburetor warm and aid in its operation. This is particularly desirable in cool weather and 45 insures an effective operation of the carburetor.

It is to be understood that although a separate and distinct pipe has been shown in Figure 3 that the member 12 may be formed

integrally with the body portion 1 of the 50 gasket and that the term "pipe" is used in this specification and in the claim shall include this construction also.

It will thus be seen that a manifold gasket has been provided which will interrupt the 55 film of liquid fuel adhering to the walls of the intake manifold and exhaust parts, which will heat and vaporize such liquid fuel and intimately mix it with incoming air, and which will secure this heating and 60 vaporizing of the liquid fuel without injecting any of the products of combustion into the inwardly flowing stream of mixed air and fuel thus securing maximum efficiency.

It will also be seen that the gasket can be 65 very readily made and can be as readily installed with a minimum of change in the standard equipment of an automobile.

Although the invention has been described in considerable detail, it is to be understood that the invention may be variously embodied, and is, therefore, to be limited only as claimed.

I claim:

The combination of a carburetor and an 75 intake manifold of an internal combustion engine, an exhaust manifold, and a gasket attached between said intake manifold and said carburetor, said gasket having a shoudered portion on the side adjacent the carburetor slightly constricting the continuous aperture through the intake manifold, the opening through said gasket being conical and gradually flaring towards the intake 80 manifold to the size of the intake manifold, a heating pipe supplied from the exhaust manifold and extending transversely across the opening through said gasket, said gasket having an air inlet duct opening tangentially into the aperture through said gasket 85 at a point spaced rearwardly from said shoulder.

In testimony that I claim the foregoing I have hereunto set my hand at Milwaukee, 90 in the county of Milwaukee and State of Wisconsin.

WALTER J. BLIFFERT.
